UNITED STATES PATENT OFFICE.

WILLIAM F. DURYEA, OF HACKENSACK, NEW JERSEY.

DESIGN FOR A PEN OR PENCIL RETAINER.

No. 39,989.

Specification for Design.

Patented May 18, 1909.

Application filed January 15, 1909. Serial No. 472,555. Term of patent 3½ years.

To all whom it may concern:

Be it known that I, WILLIAM F. DURYEA, a citizen of the United States, and a resident of Hackensack, in the county of Bergen, State of New Jersey, have invented a new, original, and ornamental Design for a Pen or Pencil Retainer, of which the following is a specification, reference being had to the accompanying drawings, forming a part thereof, wherein—

Figure 1 illustrates a front view of my design, Fig. 2 a side view, and Fig. 3 a rear view.

I claim—

The ornamental design for a pen or pencil retainer, substantially as shown.

WILLIAM F. DURYEA.
